UNITED STATES PATENT OFFICE.

CHARLES ALFRED ENSOR, OF WELLINGTON, ENGLAND.

BOTTLE-WASHING MACHINE.

1,191,776.

Specification of Letters Patent. Patented July 18, 1916.

Application filed October 29, 1915. Serial No. 58,668.

To all whom it may concern:

Be it known that I, CHARLES ALFRED ENSOR, a subject of the King of Great Britain, residing at Wellington, county of Shropshire, England, have invented certain new and useful Improvements in Bottle-Washing Machines, of which the following is a specification.

This invention relates to bottle-washing machines of the kind comprising a series of radially-arranged bottle-carrying arms, hinged to a central carrier or driving element to which an intermittent rotatory motion is imparted, and running upon a track or race of cam formation, so that as the arms revolve the bottles carried thereby are immersed within the washing water contained within a tank and are successively brought to rest opposite one or more reciprocating brushes which are automatically operated so as to scour the interior, or interior and exterior, of the bottles; the said carrier arms, after passing the brush or brushes, being caused by the cam track to rise and lift the bottles clear of the water.

In the previous arrangement the cam track was situated within the tank, carrier arms having rollers or bearers immersed within the water and running upon the track; the pivots of the carrier arms being also situated within the water.

The principal object of the present invention is to insure that the bearers and pivots or other working parts shall not be immersed in the water, so that no corrosion of the working faces can take place due to any acids that may be present in the water; this object being attained by providing the cam track above the surface of the water, the bearers preferably being carried by extensions of the arms beyond the pivots, so as to engage beneath the fixed cam.

Other objects of the invention are to improve and simplify the means for imparting the intermittent motion to the carrier; to provide improved means for operating the reciprocating brushes so as to prevent damage occurring should the brush meet with an obstruction on entering the bottle; to improve the arrangement of the brushes for cleaning the outsides of the bottles; and to provide improved means for rinsing the bottles after they have been removed from the washing water.

Figure 1 of the accompanying draw-

ings represents a vertical section through a bottle-washing machine constructed in accordance with this invention, showing the bottle-washing mechanism. Fig. 2 is another section showing the mechanism for use in connection with the rinsing of the bottles. Fig. 3 is a plan of the machine. Fig. 4 illustrates a detail in connection with the valve used for controlling the supply of water to the rinsing nozzles. Fig. 5 is a longitudinal section through the brush carriage, showing how the brush spindles are driven. Fig. 6 represents a cross-section on line x , Fig. 5. Fig. 7 is another cross-section through the brushes for the outside of the bottles and through the guide rods of the brush carriage, showing the latter in end elevation. Fig. 8 shows a section taken on line x' , Fig. 1, upon a larger scale, illustrating the pulley clutch and worm driving mechanism. Fig. 9 is a view of the intermittent driving gear for the rotation of the bottle carrier.

The improved bottle-washing machine (see Fig. 1) comprises a central vertical standard 1 fixed within a hollow column or socket 2. A boss 3, forming part of the rigid frame of the machine, has projecting therefrom a horizontal shaft 4 upon which is rotatably mounted a sleeve 5 having keyed thereupon a worm-wheel 6 driven from a worm shaft 7 which is rotated by a pulley 8 fitted with the usual clutch 9 and disengaging gear 10 (see Fig. 8). The sleeve 5 carries a bevel pinion 11 having only a single tooth (see Fig. 9) adapted to engage with and rotate a horizontal bevel wheel 12 having a series of gaps or spaces in its periphery which are engaged in turn by the single tooth. The bevel wheel 12 is keyed to the boss 13 of the horizontal carrier disk 14 free to turn about the shaft 1, and to which are hinged the rising and falling bottle-carrying arms 15. During one complete revolution of the pinion 11 the horizontal wheel 12 is moved by the single tooth through a space equal to the distance between two gaps or teeth, thus moving the bottle arms 15 one step.

Fixed concentrically with respect to the standard 1 is an annular tank or trough 16 into which depend the radially-arranged bottle-carrying arms 15, said arms being pivoted at 17 (above the water level) to the edge of the horizontal carrier disk 14 and

being extended beyond or inward of the pivots into short arms 18 formed with bearing surfaces 19 which engage with the edge of a depending cam flange 20 of a plate or disk 21 surrounding the boss of the bevel wheel 12 but held stationary by being fixed to the worm-gearing casing 22. The depth of the flange 20 varies at different points in its circumference. When the bearing surfaces 19 engage with the lower portion of the flange the bottles lie in a horizontal position above the water (Fig. 1) or above the horizontal (Fig. 2), whereas when they engage with the highest portion the bottles are wholly immersed in the water, and lie more or less obliquely (right-hand side of Figs. 1 and 2). The weight of the bottles maintain the arms in engagement with the cam.

As the carrier arms 15 are brought to rest by the intermittent drive, a pair of bottles come to rest opposite to a corresponding set of brushes (see Fig. 1). The brush gear comprises a reciprocating carriage or saddle 23 sliding upon guide rods 24 and carrying two brushes 25 adapted to be forced into the interior of the bottle. The carriage carries a pulley 26 (see Figs. 5 and 6) which is feathered upon a square or other driving shaft 27 supported by a fixed bracket 28. This shaft 27 has fixed to it a pulley 29 driven from a pulley 30 on the worm shaft 7 by a belt or band 31 passing around guide pulleys 32, 33, carried by suitable brackets.

The main pulley 26 upon the saddle drives, by means of a belt 34, the spindles 35 of the two brushes 25 for cleaning the inside of the bottles. For cleaning the outsides of the bottles three concave revolving brushes 36 are employed (see Fig. 7), same being carried upon spindles 37 arranged at right angles to the axes of the bottles and adapted to engage with opposite sides of the bottles, the middle one coming between the two bottles. The spindles 37 of these external brushes carry at their upper ends pulleys 38 driven by a band 39 (see Figs. 3, 5 and 7) from a pulley 40 driven by bevel gear 41 from the main pulley 26.

The brush carriage 23 is moved so as to force the brushes 25 into the bottles by means of a weight 42 which, by means of a cable 43 rotates a pulley 44 (see Fig. 1) mounted upon a spindle to which is fixed an arm 45 connected to the carriage through the medium of a connecting rod or link 46, so that as the weight descends the arm and connecting rod move the carriage forward and downward, causing the inner brushes 25 to pass into the interior of the bottles, and the revolving concave brushes 36 to pass over the outsides of the bottles. Should the brushes meet with an obstruction the descent of the weight 42 is arrested, no damage resulting as would be the case if the brushes were posi-

tively operated by means of a cam. To withdraw the brushes a horizontal cam 49 is fixed upon a sleeve 47 surrounding the upper part of the standard 1 and driven by a bevel wheel 48 on the sleeve 5. This cam 49 operates a sliding rod 50 having a pin 51 engaging a slot 52 in an arm 53 fixed to the shaft of the pulley 44. The travel of the carriage can be altered to suit different sizes of bottles, by means of an adjustable screw stop 54. The end of the rod 50 adjacent to the cam carries a cage or frame 72 supported and guided in its reciprocating movement by the boss of the cam 49, as shown in Fig. 1. The said guide frame 72 carries a roller 73 with which the cam engages. The said cam is of the shape shown in Fig. 3, so that as the narrower part of the cam comes opposite the roller it allows the rod 50 to be moved inward by the weight 42 until the stop 54 comes against the fixed part 74. By lengthening the stop 54 the amount of travel of the brush carriage is reduced.

In order to accurately center the bottles while the brushes are being passed into the interior, two centralizing forks 55 are provided slightly in advance of the brushes, these forks being carried on sliding rods 56 forced by springs 57 but which are moved back by the carriage, when the latter is fully withdrawn, so that the forks 55 are just clear of the bottles. When, however, the carriage moves forward the rods 56, due to the action of the springs 57, follow the carriage movement until the forks engage with the bottle necks, thus centralizing said bottles. The forks are kept pressed against the bottle necks until the carriage on the return movement overtakes the rods and releases the bottles before the carrier arms 15 are moved away to bring a fresh set of bottles into position.

In order to effectually clean the bottoms of the bottles either fixed or rotary brushes may be employed within the tank.

On the withdrawal of the brushes the bottles which have been cleaned are moved forward into the position shown in Fig. 2, coming to rest opposite to a pair of nozzles 58 from which a jet of fresh water is directed into the bottles for rinsing. The nozzles slide in housings 59 carried by brackets 60 on the fixed cam plate 21 and tend to be forced forward into the bottle necks by springs 61. They are adapted to be withdrawn by a lever 62 connected by rod 63 to bell-crank lever 64 actuated by a cam 65 fixed on bevel wheel 48. The said cam comes into action while the carrier arms and bottles are being moved through the interval necessary for the introduction of a fresh set of bottles before the respective brushes, when the cam allows the springs 61 to move the nozzles against the bottle mouths. A perforated pipe 66 sprays water upon the out-

sides and ends of the bottles. A controlling valve 67 is employed (see Figs. 3 and 4) whose spindle has a trip lever or arm 68 which is engaged by a pin 69 on the sliding 5 rod 50, so that the forward movement of the brush carriage turns on the water to the rinsing jet, while the reverse movement turns off the water owing to the pin 69 engaging with a second arm 70 on the valve 10 spindle. A pipe 71 leads from the valve to the nozzles.

Having fully described my invention, what I desire to claim and secure by Letters Patent is:—

- 15 1. A bottle-washing machine comprising a central driving element, means for imparting an intermittent rotatory motion thereto, a series of radial bottle-carrying arms pivoted to the driving element, a tank for 20 containing the washing liquid, a sliding brush carriage, brushes carried thereby, a stationary cam track engaged by the bottle-carrying arms and adapted to operate said arms to cause the bottles to be immersed 25 into and brought out of the liquid, said arms being adapted to move past the brushes, a weight for moving the brush carriage forward to cause the brushes to engage with the bottles when successively brought to 30 rest opposite said brushes, and a cam for returning the brush carriage and withdrawing the brushes.
2. A bottle-washing machine comprising a central driving element, means for imparting an intermittent rotatory motion thereto, a series of radial bottle-carrying arms pivoted to the driving element, a tank for containing the washing water, a stationary cam track engaged by the bottle-carrying 35 arms and adapted to operate said arms to raise and lower the bottles into and out of the water, a sliding brush carriage, brushes carried thereby for cleaning the interior of the bottles, a brush driving shaft, a driving 40 wheel mounted within the carriage and feathered upon the driving shaft, means for rotating the brush spindles from said driving wheel, revolving brushes for the outsides of the bottles, revolving spindles carrying 45 said brushes and arranged at right angles to the axes of the bottles, means for rotating said spindles from the brush driving shaft, means for moving the brush carriage forward to cause the brushes to engage with 50 the bottles, and a cam for returning the brush carriage and withdrawing the brushes.
- 55 3. A bottle-washing machine comprising a central driving element, means for imparting an intermittent rotatory motion thereto, a series of radial bottle-carrying arms pivoted to the driving element, a tank for containing the washing liquid, a stationary cam track engaged by the bottle-carrying arms and adapted to operate said arms to raise and lower the bottles into and out of the liquid, a sliding brush carriage, brushes carried thereby, a pulley, a weight attached to 60 the pulley by a cable, a pair of arms fixed to the pulley, a connecting rod between one of said arms and the carriage, a sliding member, a main driving shaft, a cam on said main driving shaft and engaging with the 65 sliding member, a connection between said sliding member and the other arm of the pulley, bottle-rinsing nozzles, a controlling valve for the rinsing water, and an arm on said valve which is operated from the slid- 130
- 75 4. A bottle-washing machine comprising a central driving element, means for imparting an intermittent rotatory motion thereto, a series of radial bottle-carrying arms pivoted to the driving element, a tank for containing the washing liquid, a stationary cam track engaged by the bottle-carrying arms and adapted to operate said arms to raise and lower the bottles into and out of the liquid, a sliding brush carriage, brushes carried thereby, a weight for moving the brush carriage forward to cause the brushes to engage with the bottles, a cam for returning the brush carriage and withdrawing the brushes, a conical bottle-centering device, 80 and means for moving said device into engagement with the neck of a bottle to center the latter while the brush is passed into same.
- 85 5. A bottle-washing machine comprising a central driving element, means for imparting an intermittent rotatory motion thereto, a series of radial bottle-carrying arms pivoted to the driving element, a tank for containing the washing liquid, a stationary cam track engaged by the bottle-carrying arms and adapted to operate said arms to raise and lower the bottles into and out of the liquid, sliding bottle-rinsing nozzles, a 90 spring for moving said nozzles into the bottle necks when the bottles are raised out of the liquid and brought to rest, and a lever for withdrawing said nozzles, and a cam for actuating the lever.
- 95 6. A bottle-washing machine comprising a central driving element, means for imparting an intermittent rotatory motion thereto, a series of radial bottle-carrying arms pivoted to the driving element, a tank for containing the washing liquid, a stationary cam track engaged by the bottle-carrying arms and adapted to operate said arms to raise and lower the bottles into and out of the liquid, a sliding brush carriage, brushes carried thereby, a pulley, a weight attached to 100 the pulley by a cable, a pair of arms fixed to the pulley, a connecting rod between one of said arms and the carriage, a sliding member, a main driving shaft, a cam on said main driving shaft and engaging with the 105 sliding member, a connection between said sliding member and the other arm of the pulley, bottle-rinsing nozzles, a controlling valve for the rinsing water, and an arm on said valve which is operated from the slid- 110
- 115

ing member employed for withdrawing the brush carriage so as automatically to turn the water on and off as required.

7. A bottle washing machine comprising,
5 a central driving element adapted to rotate in a horizontal plane, means for imparting an intermittent motion to said element, a series of radially arranged bottle supporting arms pivoted to said element at a point
10 above the surface of the washing fluid, said arms having extensions extending inwardly from their pivots, a reciprocating brush geared for scouring the bottles, a stationary track having a cam surface situated above
15 the surface of said fluid and constantly engaged by said inward extensions to said bottle supporting arms so as to cause the bottles to be immersed and successively brought out of said fluid to rest opposite said brush,
20 and means for automatically reciprocating said brush when the bottles are at rest.
8. A bottle washing machine comprising,
a central driving element, a series of radially arranged bottle carrying arms pivoted
25 to said element, a tank for containing washing fluid, a sliding brush carriage, brushes carried by said carriage, a cam track arranged to be engaged by said brush carrying arms and to operate the latter to
30 cause said bottles to be raised and lowered into and out of the said fluid, said bottles being adapted to pass said brushes, means for moving said carriage forward to cause the brushes to engage with the bottles when
35 successively brought out of the fluid and at rest opposite said brushes, and means for returning said brush carriage and withdrawing said brushes when said element is again actuated.
- 40 9. A bottle washing machine comprising, a central driving element, means for rotat-

ing said element, a series of radially arranged bottle carrying arms pivoted to said element, a tank for containing washing fluid, a cam surface engaged by said arm 45 and adapted to operate the latter to raise and lower the bottles into and out of the fluid, a sliding brush carriage, brushes carried by said carriage, means for automatically moving said brush carriage forward 50 to cause said brushes to engage with said bottles at a predetermined point in the rotation of said element, and means for automatically returning said brush carriage and withdrawing said brushes. 55

10. A bottle washing machine comprising, a central driving element, means for rotating said element, a series of radially arranged bottle carrying arms pivoted to said element, a tank for containing washing 60 fluid, a cam surface engaged by said arm and adapted to operate the latter to raise and lower the bottles into and out of the fluid, a sliding brush carriage, brushes carried by said carriage, means for automatically moving said brush carriage forward 65 to cause said brushes to engage with said bottles at a predetermined point in the rotation of said element, a bottle centering device, means for moving said device into 70 engagement with the bottle when the latter is to be operated upon by said brushes, and means for automatically returning said brush carriage and withdrawing said brushes. 75

In testimony whereof I have hereunto set my hand in presence of two subscribing witnesses.
